(57) **CLAIM**

The ornamental design for a dongle, as shown and described.

DESCRIPTION

FIG. 1 is a perspective view of a dongle according to an embodiment of the invention;

FIG. 2 is a front view of the dongle according to FIG. 1;

FIG. 3 is a back view of the dongle according to FIG. 1;

FIG. 4 is a left side view of the dongle according to FIG. 1;

FIG. 5 is a right view of the dongle according to FIG. 1;

FIG. 6 is a top view of the dongle according to FIG. 1; and,

FIG. 7 is a bottom view of the dongle according to FIG. 1.

The broken lines showing of the connectors and various regions of the dongle in FIGS. 8–14 are for the purpose of illustrating environmental structure and form no part of the claimed design.

1 Claim, 7 Drawing Sheets
